UNITED STATES PATENT OFFICE.

WILLIAM H. CLARKSON, OF EDWARDS STATION, ILLINOIS, ASSIGNOR TO
ELUIDE J. CLARKSON, OF EDWARDS STATION, ILLINOIS.

COAL-DRILL.

No. 802,197.

Specification of Letters Patent.

Patented Oct. 17, 1905.

Application filed March 4, 1904. Serial No. 196,622.

To all whom it may concern:

Be it known that I, WILLIAM H. CLARKSON, a citizen of the United States, residing at Edwards Station, in the county of Peoria and State of Illinois, have invented certain new and useful Improvements in Coal-Drills; and I do hereby declare that the following is a full, clear, and exact description of the invention, which will enable others skilled in the art to which it appertains to make and use the same.

This invention relates to improvements in coal-drills.

The object of the invention is to provide an improved form of drill-frame and, further, to provide a new form of boxing for the thread-bar.

A still further object is to provide an improved drill for assisting in the boring operation.

The invention relates also to various details of construction and arrangement of parts, as will be described in the following specification.

In the annexed drawings, Figure 1 is a front elevation of the drill set up for use. Fig. 2 is a side view of the same. Fig. 3 is a top view of boxings and driving-gears with the thread-bar and showing the frame in cross-section. Fig. 4 is an end view of the thread-bar, showing a portion of a crank clamped thereto. Fig. 5 is a perspective view of a boxing and its inclosing member shown in the other figures. Fig. 6 is a perspective view of a U-shaped support for the member shown in Fig. 5. Fig. 7 is a longitudinal section of my improved form of drill, showing a tubular extension thereof and a chuck member within the hollow thread-bar. Fig. 8 is a vertical section of the inclosing member shown in Fig. 5 with a half-boxing for the thread-bar therein. Fig. 9 is a perspective view of my improved drill. Fig. 10 is a perspective view of a modified form of drill. Fig. 11 is a longitudinal section of the same. Fig. 12 is a general view of the machine when at work. Fig. 13 is a top view, in part section, of a thread-bar boxing; and Fig. 14 is an end view of the same.

Figs. 1 and 2 show the complete machine, wherein—

A A are two frame-sections of U form, secured together to constitute a hollow support, as shown. The lower extremities of these sections are bolted together at B, the upper ends being free and having between them a

bar C, whose upper end terminates in a threaded section having an internally threaded sleeve D thereon, said sleeve having a pin E therein, by which to turn it. A loose collar F is placed upon and surrounds the upper ends of the frame, and by means of a screw G therein the said frame ends are clamped tightly together with the bar C between, and by this means the said bar can be adjusted vertically as desired. The sleeve D is pointed, as also is the lower end of the frame A, so that these extremities may be forced into the ceiling and floor of the mine, and then by turning the sleeve the frame may be tightened in position for work, all of which will be understood. An adjustable support H is provided, Fig. 6, for insertion between the limbs of the frame, there being a pair of holes therein to register with pairs of holes I in the frame, as shown in Fig. 2. A U-shaped member J is inserted in the holes of the frame where desired and made to enter the pair of holes in the said support H, thus holding that member rigid. The extremities of the support extend beyond the frame and carry pivotally a tilting member K by means of one of its extremities L. A bolt or pin M, passed through the extremities of the support, also passes through the said member K and forms the pivot therefor. Within the said member K is a threaded boxing for the thread-bar N. This boxing (indicated by O) is made in two halves, as in Fig. 5, the abutting surfaces lying in a vertical plane. The arrangement of these parts is such that the pin M, on which the member K is supported and pivots, enters a notch P in both boxing-sections, and thus prevents them leaving the member and also serves to keep them in perfect register at all times. By withdrawing the pin M the member K may be removed from its place and the boxing-sections pushed out and repaired or replaced with another pair. Made with the said member K is an arm Q, whose free end constitutes a boxing for supporting a shaft R. This shaft carries a beveled wheel or gear S, which meshes with a similar one, T, on the thread-bar N. The thread-bar has a keyway at U, and a key V held in the gear serves to revolve the said thread-bar, while permitting the latter to progress through the boxing O. It is evident that the said gear T is bored out smooth to permit the thread-bar to freely pass therethrough, its hub bearing

against the boxing O and the member K. The latter is provided with two projections L, in order that it may be reversed or placed in any desired position, so that in working in cramped places some adjustment may be had that will permit the work to easily proceed.

The drill shown in the drawings is, in so far as I am aware, novel in its construction and is likewise new for the purpose of drilling coal. As shown in Figs. 2, 7, and 9, it consists of a tubular member W, of cone shape, its small or contracted end having connection with a tube X, carried within the thread-bar U. The outer or large end of the drill is dished, and the dished face is provided with a series of radiating cutting-teeth Y. This member W may be removed from the tube X for sharpening by removing a screw Z, which passes through a flange of said member and a reduced projection on the tube X, as indicated in Fig. 7. However, other means may be used to secure these members together, as will be understood. The opposite end of the tube X is cut out to form projecting tongues, only one of which is shown in Fig. 7 by the numeral 2. These tongues are designed to engage with a removable sleeve 3 in the end of the tube, said sleeve having a notch in each end, as shown at 4. As shown in Fig. 4, the sleeve is merely a piece of tubing, the notches 4 being cut at diametrically opposite sides thereof, thus constituting a chuck, it being understood that the tube X has the tongues 4 to engage therewith. A free passage is thus left entirely through the thread-bar. The sleeve is held in place by means of a pin 5, which may be withdrawn when desired to release the sleeve. In Figs. 2 and 6 the drill-tube X is inclosed in the thread-bar, and as the latter works through the boxing O during the drilling operation its limit of travel is finally reached, after which no more drilling can be done. At this time the drill is withdrawn from the thread-bar and the latter is turned end for end by swinging the frame A on its pivots above and below. This allows the thread-bar to operate again in the same manner as before; but this time the drill-tube is seated in the outer end of the sleeve 3, as shown in Fig. 12. This allows the operator to increase the length of his drilling apparatus without moving the machine from its original position. Holes 6 at the opposite end of the thread-bar permits the sleeve 3 to be located in the thread-bar at that end if for any reason it is desired to do so, or in preference to this the thread-bar after carrying the drill as far as it will go when arranged as in Fig. 7, the said thread-bar may be withdrawn from the hole leaving the drill. Then the chuck may be removed from its position and placed in the end of the thread-bar just withdrawn from the hole. The drilling may then proceed as before, it having been unnecessary to reverse the position of the supporting-frame. In use

the drill cuts away the material into which it is at work, and said material passes back through the tube X since there is no other outlet and since there is a continuous outlet entirely through the thread-bar, the drill is kept cleared at all times, as will be evident.

In Figs. 10 and 11 is illustrated a modified form of my drill. This form is merely a plate 7 of the desired size having the cutting edges 8, while between them are openings 9 for the escape of the loose material. The openings are created by punching the metal out and bending the portions down, as shown. These portions are then used to secure the drill to a carrying-tube 10, as before.

80

I provide for the drilling-machine a crank, as shown, which may be used on the shaft of the gear S or upon the thread-bar, according to the place in which the drill may be in use. In some places it may be more convenient to use the crank on the thread-bar than on the shaft of the said gear, or vice versa. In order that the crank may be made to fit both the thread-bar and the shaft, the latter is provided with an enlargement of substantially the same size as the thread-bar, so that said crank may be as easily clamped to one as the other by means of a thumb-nut or other convenient means.

85

In Figs. 13 and 14 I show the form of inclosing member desired to hold the boxing O. It will be seen that in preference to making the boxing so that it will just fit into the member the opening in the latter is made slightly larger than the boxing, as shown in said figures, so that one of the sections may be shifted to one side in order to release the thread-bar. Near each end of the housing is a key O', inserted in a hole provided for its reception, and said keys serve to push the boxing back into position when the thread-bar is entered. It will thus be seen that at any time or place the bar can be easily removed without the necessity of entirely removing the boxing from its position.

100

I have shown in Figs. 1, 2, and 4 the crank for turning the thread-bar clamped upon that member; but I desire to state that it may also be entered through a suitable opening at the end of said bar and held by any good means, taking the place of the pin 5, (shown in Fig. 7,) if desired.

105

I claim—

1. In a coal-drill, a supporting-frame comprising two U-shaped portions secured together rigidly at one end, means for clamping the opposite ends together, and an adjustable bar therebetween adapted to be clamped by said means for the purposes set forth.

110

2. In a coal-drill, a supporting-frame comprising two U-shaped members secured together to form an open frame, said members rigidly secured together at one end, the opposite ends being free but adapted to be clamped together, means for clamping said ends, a vertically-adjustable thread-bar be-

115

120

125

130

tween said ends and a threaded sleeve for said thread-bar substantially as set forth and for the purposes described.

8. In combination with the supporting-frame of a coal-drill, a thread-bar, a split boxing therefor, there being apertures through the housing and boxing and a pin for passing through one of the apertures for preventing movement of the boxing from the housing, said pin also pivotally securing the housing to the frame substantially as described.

9. In combination with the supporting-frame of a coal-drill a reversible housing pivoted on said frame, an internally-threaded boxing of two sections within the housing, there being apertures through the housing and the two sections, an aperture being at the top and one at the bottom and a pivot-pin for entering one or the other of the apertures and the supporting-frame to form a pivot on the frame for the housing and for securing the boxing-sections in place the housing being vertically reversible by means of the two apertures and the pin.

10. In a coal-drill mechanism comprising a supporting-frame reversible by a turn on its pivot, a drill-carrying support on the frame, a hollow thread-bar adapted to progress through the said support during revolution thereof, a removable double-ended clutch adapted to be secured in either end of the hollow thread-bar, a drill adapted to seat in the chuck and lying inclosed in the thread-bar as shown and driven by the revolution of said thread-bar, the drill adapted also to seat in the outer end of the chuck after turning the frame on its pivots for the purposes described.

11. A coal-drill comprising a supporting-frame reversible by a turn on its supports as described, a drill-supporting mechanism carried on the said frame, a hollow drill-carrying thread-bar adapted for progressive movement through the said drill-supporting mechanism during its revolution, a drill, a drill-chuck removably secured in either end of the thread-bar, said drill lying within the said thread-bar and held by the chuck at the farthest end of the latter when starting a boring, the position of the chuck being changed after drilling the hole to the limit of movement of the thread-bar, to continue the drilling for the purposes described.

In testimony whereof I affix my signature in presence of two witnesses.

WILLIAM H. CLARKSON.

Witnesses:

L. M. THURLOW,
E. J. ABERSOL.

3. A coal-drill frame, comprising an open rectangle, and having an extended pointed lower end for anchoring purposes, the opposite end being open, a bar slidable between the extremities of the open end and having contact with said ends and threaded at its free end, a collar surrounding the bar and the extremities of the frame for clamping the said bar between said extremities and an internally-threaded sleeve on the threaded end of the bar, the same being pointed for anchoring purposes substantially as shown.
4. A coal-drill frame comprising an open rectangle, having an extended pointed lower end for anchoring purposes, the opposite end being open, a bar adapted to be clamped between the extremities of the open end and having slidable contact therewith and threaded at its upper free end, a collar inclosing the open ends of the frame and the thread-bar, a screw in the collar for clamping it to the frame ends and clamping the thread-bar between the said ends, and a pointed internally-threaded sleeve for said thread-bar substantially as shown and described.
5. In a coal-drill, a supporting-frame comprising the members A of the form shown, the same being rigidly secured together at their lower ends, the upper ends thereof approaching one another, the adjustable bar C between said ends all adapted to be clamped together, said bar having sliding contact with the frame ends, a collar F surrounding the ends and the bar, the screw G for clamping them, the adjusting-sleeve D on said bar C and the drill pivotally supported on the frame substantially as described and shown.
6. A coal-drill frame comprising an open rectangle having an extended pointed end, for anchoring purposes, the opposite end being open, a bar between the extremities of the open ends of the frame and having slidable contact therewith and threaded at its upper free end, a collar inclosing the open ends of the frame and the thread-bar, a screw in the collar for clamping it to the frame ends and clamping the thread-bar between the said ends, a pointed internally-threaded sleeve for the said thread-bar, and a series of holes in the frame throughout its entire length substantially as shown and described.
7. In combination with the supporting-frame of a coal-drill, a split thread-bar boxing, a thread-bar for the same, a housing for the boxing and a pivot-pin for supporting the housing on the said frame, there being apertures through the housing and boxing through which the said pin passes to lock the boxing in place substantially as described.
